UNITED STATES PATENT OFFICE.

J CORBLEY POOL, OF SANTA BARBARA, CALIFORNIA, ASSIGNOR OF ONE-HALF TO W. B. POOLE, OF SANTA BARBARA, CALIFORNIA.

HYDROCARBON STILL.

Application filed February 18, 1920. Serial No. 359,505.

To all whom it may concern:

Be it known that I, J CORBLEY POOL, a citizen of the United States, residing at Santa Barbara, in the county of Santa Barbara and State of California, have invented certain new and useful Improvements in a Hydrocarbon Still, of which the following is a specification.

This invention relates generally to improvements in apparatus for effecting fractional distillation of hydro-carbon oils, and more particularly the invention aims to produce a maximum quantity of gasoline and motor oils from a given quantity of crude petroleum.

Among other and equally important objects of the invention are: to provide means whereby the formation of cake in a still will be decreased to prevent, among other things, the burning out of the still; to improve upon prior means for heating the still to attain a maximum heating efficiency for a given amount of fuel; to effect direct and continuous removal of sludge, tar and residuum from the still during the process of distillation; to provide for the direct return of all hydrocarbon distillates of a specific gravity greater than gasoline to the still for re-distillation or "re-cracking;" to attain positive regulation of pressure within the various elements of the apparatus; and to improve upon prior methods and apparatus for isolating the desired distillates.

In order to define the invention in general terms it is pointed out that the still is arranged at an incline to the furnace and communicates at its lower end with a storage tank for receiving sludge, tar and other residuum. Extending through the still are heating tubes and the exterior walls of the still are spaced from the walls of the furnace to effect a return draft to the chimney in order to attain a maximum efficiency of the furnace. Communicating with the upper end of the still is a vapor dome or tower to permit condensation and return of the heavier hydro-carbons to the still, and connected with the vapor dome or tower is a primary condenser provided with baffle plates associated with heating elements and divided into compartments for isolating the desired distillates. In the primary condenser the heavier hydro-carbons are drained back to the still, the gasoline and naphtha

tapped to storage tanks, and the lightest vapors carried to a secondary condenser having atmospheric temperature and pressure.

For the purpose of illustrating this invention, there is shown in the accompanying drawings one form thereof which is at present preferred, since the same has been found in practice to give satisfactory and reliable results, although it is to be understood that the various instrumentalities of which the invention consists can be variously arranged and organized and that the invention is not limited to the precise arrangement and organization of these instrumentalities as herein shown and described:—

In the drawings:—

Figure 1 is a side elevation of the apparatus in its entirety showing the furnace and still in section.

Figure 2 is a view on the line 2—2 of Figure 1.

Figure 3 is a view on the line 3—3 of Figure 1.

Figure 4 is a view on the line 4—4 of Figure 1.

Figure 5 is an enlarged longitudinal section taken through the primary condenser.

Figure 6 is a detail view of one of the baffle plates and heating elements of the condenser, and

Figure 7 is a view of another of the baffle plates and heating elements which constitute also a partition for dividing the primary condenser into compartments.

In the drawings wherein like characters of reference indicate like or similar parts:—

A designates the fire box of a furnace which in this instance is provided with a communicating chamber 5 adjacent the rear wall 6 of the fire box and between which and the fire box is arranged a foraminated or slotted arch 7 for breaking the flame blast. Extending into the chamber 5 is a recording pyrometer for an obvious purpose. Adjacent the upper end of the chamber 5 the front wall of the furnace is enlarged as at 8 and arranged at an incline to the chamber and with its end resting upon the enlargement 8 and upon the rear wall 6 of the firebox is a still B.

The portion of the furnace to the rear and above the fire box is built out as at C and has a central cavity 9 of greater size than

the still B which is arranged therein so that the heated air which passes through the open heating tubes 10 arranged longitudinally and extending from end to end of the still will pass out the upper ends thereof, around the outside of the still and up into the smoke chamber 11 of the furnace which communicates with the chimney D. As clearly illustrated in Figures 2 and 3 the 10 spaces between the still and the walls of the cavity 9 have arranged therein casings 12 which conform to the shape of the spaces and serve to support the still in addition to protecting the walls thereof and the walls 15 of the cavity. The upper portion of the wall of the still lies against the walls of the cavity and the upper end of the still terminates short of the end wall of the cavity. A manhole 13 having a cover 14 is arranged 20 at this point in the end wall of the cavity for cleaning the same when it becomes necessary. From the foregoing it will be seen that the hot air blast from the furnace is carried through the tubes 10 into the cavity 25 9 and around the still B into the smoke chamber 11 and from thence to the chimney D; consequently effecting uniform heating of the still and attaining a maximum heating efficiency.

30 Communicating with the lower portion of the still B and arranged in a recess in the rear portion of the rear wall 6 of the furnace is a settling or storage tank E for receiving sludge, tar and other residuum for the still. 35 The peculiar arrangement of the settling tank E permits the sludge or tar to pass directly thereto from the still during the process of distillation and the inclination of the still and arrangement of the heating apparatus greatly decreases the formation of cake 40 therein. A recording pyrometer and a manhole 15 are arranged in the settling tank E, and an outlet pipe 16 having a valve 17 communicates therewith for draining its contents. Furthermore, as the still will probably be operated under pressure a pressure line communicates therewith and is provided with a recording dial 18 of the usual type; while a manhole 19 permits cleaning the still 45 when it is so desired.

50 Communicating with the still B at a point adjacent the upper end thereof is a vapor dome or tower F which in turn communicates with a primary condenser G through 55 a conduit 20, and extending through the wall of the tower or dome and passing to the still is a crude oil supply pipe 21. In operation the vapors arising from the still pass upwardly into the dome or tower F where 60 the heavier vapors condense and the lighter vapors pass on through the conduit 20 to the primary condenser G.

65 The primary condenser G has arranged therein baffle plates 22 and 23 extending respectively from the top and bottom of the condenser and each terminates short of the opposite wall. Those baffle plates 23 extending from the bottom also serve to divide the condenser into a plurality of distillate receiving compartments as illustrated 70 in dotted lines in Figure 1. Hereinafter these compartments will be designated by G^a, G^b, G^c, G^d, G^e and G^f beginning with the compartment nearest the dome or tower F. Lying against the walls of each of the baffle 75 plates are heating coils 24 which branch from a service pipe 25 communicating with a steam inlet pipe 26 extending to a boiler (not shown), and each coil branch is provided with a valve 27 for regulating the admission of steam to the several coils in order to attain different temperatures in the various compartments to produce the desired 80 distillates. A plurality of recording pyrometers 28 are also provided, one of each of which communicates with each of the several compartments. The dead steam is carried off by a pipe line 29 which may lead to a superheater (not shown) if desired. Communicating with each of the compartments 85 through the bottom portion of the condenser are outlet pipes 30 which communicate with a drain pipe 31 extending to the still for returning residuum and the heavier hydrocarbons for redistillation or "cracking," and 90 in each outlet pipe is carried a valve 32. As the heaviest hydrocarbons are designed to be condensed in compartments G^a and G^b they are immediately carried to the still for redistillation, but as the gasoline, naphtha, 95 etc., are condensed in compartments G^c, G^d, G^e and G^f branch conduits 33 are tapped into outlet pipes 30 of these compartments above the valves 32, so that upon closing the 100 valves 32 these distillates will immediately be carried to the storage tanks indicated in Figure 1 and designated for the sake of clarity by the numerals 34. With reference to the foregoing it is to be understood that the temperature in the several compartments 105 may be regulated by the valves 27 to produce the desired distillates; these temperatures being indicated by the recording pyrometers 28.

110 A secondary condenser H is connected with the rear end of the primary condenser by a conduit 35 which has mounted thereon a pressure gage 36 and a relief valve 37; it being desirable to reduce the pressure to normal or atmospheric pressure after the 115 remaining vapors leave the primary condenser. The secondary condenser is formed with a plurality of coils 38 formed by bends in the conduit 35 and these coils are at atmospheric temperature and pressure in order to condense and carry off the remaining distillates from the primary condenser after the gasoline or #1 and #2 distillates, and the naphthas, 45 and 50 have been removed. 120 No storage tank is shown in conjunction 125

130

with the secondary condenser H but it is to be understood that the conduit discharges into a suitable storage tank at some other point in the vicinity of the apparatus.

- 5 In operation, the crude oil is admitted to the still B through pipe 21 and as the hot air blast passes through the tubes 10 and about the still through the flue or cavity 9 the process of distillation takes place, whereupon the 10 vapors rise within the dome or tower F and the lighter vapors are carried through the conduit 20 to the primary condenser G. The heavier vapors in the dome or tower F are condensed and return to the still for re-distillation or "re-cracking" and tar, sludge and other residuum settles to the tank E. Upon entering the primary condenser G (in which the temperature in the respective compartments G^a, G^b, G^c, G^d, G^e and G^f have 15 been regulated through manipulation of valves 27) the heavier distillates are condensed in compartments G^a and G^b and are carried to the still B through the drain pipe 31, while gasoline (#1 and #2 distillates) 20 is condensed in compartments G^c and G^d and 45 and 50 naphtha is condensed in compartments G^e and G^f and are subsequently carried off through pipes 33 to storage tanks 34, it being understood that valves 32 are 25 closed below the conduits or pipes 33. All other and lighter vapors are carried through conduit 35 to the secondary condenser where the temperature and pressure have been reduced to normal.
- 30 35 It is pointed out in connection with the present apparatus for effecting fractional distillation that the maximum efficiency is maintained through each stage of the process of distillation and all except the desired 40 distillates and extremely light vapors are returned to the still for re-distillation or "re-cracking".

From the foregoing description taken in connection with the accompanying drawing, it is thought that a clear and comprehensive understanding of the construction, operation, and advantages of the invention may be had, but while I have shown and described the device as embodying a specific 45 structure, I desire it to be understood that such changes may be made in the structure, as do not depart from the spirit and scope 50 of the invention as claimed.

What I claim is:

1. In a distilling and condensing apparatus, a furnace, an inclined still having its lower end positioned over the mouth of said furnace, means comprising fire tubes extending longitudinally through the still for directing the heated air from the furnace to the lower end of the still, then through the still to the upper end thereof and then downwardly around the outside of said still, and a settling tank communicating directly with said still and positioned without said furnace and out of contact with the heated gases from said furnace.

2. In a distilling and condensing apparatus, a furnace, an inclined still having its lower end positioned over the mouth of said furnace, means for directing the heated air from the furnace to the lower end of the still, then through the still to the upper end thereof and then downwardly around the outside of said still, a settling tank communicating directly with said still and positioned without said furnace and out of contact with the heated gases from said furnace, a vapor dome connected with said still, means extending through said vapor dome and into said still for delivering crude oil to said still, and a condenser for vapors issuing from the still connected with said vapor dome.

3. In an oil cracking and distilling apparatus, a furnace, an inclined still having its lower end positioned over the mouth of said furnace, means for directing the heated air from the furnace to the lower end of the still, then through the still to the upper end thereof and then downwardly around the outside of said still, a settling tank communicating directly with said still and positioned without said furnace and out of contact with the heated gases from said furnace, a vapor dome connected with said still, means extending through said vapor dome and into said still for delivering crude oil to said still, and a fractionating condenser for receiving the vapors evolved from said still for separating the heavy distillates and returning same to the still.

In testimony whereof, I affix my signature hereto.

J CORBLEY POOL.
